FUEL INJECTION SYSTEM

Waldo G. Gernandt, Berkeley, Calif.

Application March 15, 1937, Serial No. 130,919

5 Claims. (Cl. 123—138)

This invention relates to improvements in fuel injection systems, more particularly for Diesel motors.

The present invention is an improvement on 5 the injection unit illustrated and described in my Patent #2,061,571, issued November 24, 1936, and entitled "Engines".

Among the objects of this invention is to accomplish uniformity in the quantity, pressure, 10 and timing of fuel distributed to the several cylinders of a multicylinder motor.

Another object is to combine the fuel pump and the fuel distributor to establish precision in the coordination of these mechanisms.

15 Another object is to preheat the fuel injected into the motor.

Another object is to terminate the injection cycle sharply so as to obviate dripping of fuel at the injector.

20 Another object is to provide a fuel pump of simpler and less expensive construction.

Other objects and advantages appear as this description progresses.

In this specification and the accompanying 25 drawings the invention is disclosed in its preferred form. It is, however, to be understood that it is not limited to this form because it may be embodied in other forms within the purview of the claims following the description.

30 In the accompanying two sheets of drawings:

Fig. 1 is a vertical section of a fuel pump constructed in accordance with this invention.

Fig. 2 is a side elevation of the same, broken away in parts to disclose the underlying structure.

35 Fig. 3 is a horizontal section taken along the line III—III in Fig. 1 viewed in the direction of the arrows and illustrating the distributor head. The pump plunger is superimposed in dotted lines 40 to show its operative relation with the distributor head.

Fig. 4 is a fragmentary vertical section taken along the line IV—IV in Fig. 2 showing the passage for admitting gas to the fuel pump.

45 Fig. 5 is a similar section taken along the line V—V in Fig. 1 and showing the engagement between the pump plunger and the operating rocker arms.

Fig. 6 is a diagrammatic vertical section of 50 one of the associated motor cylinders with its fuel injector modified in accordance with the present invention.

Fig. 7 is a somewhat enlarged view of another 55 type of fuel injector suitable for use in conjunction with the present invention.

In detail, the structure illustrated in the drawings, referring more particularly to Fig. 1 comprises the pump body 1 having the hollow cylinder 2 rotatable therein within the bearing 3. The cylinder 2 has the lateral flange 4 at its upper 5 end supported by the ring 5. The annular spacer 6 confines the flange 4 against lateral movement and has the distributor head 7 superimposed thereon which is in sliding contact with the rotating flange 4. The pins 8—8 fixed in the body 1 secure the head 7 against rotary movement. The ring 5, the spacer 6, and the head 7 are clamped on the body 1 by the nut 9 threaded on the body 1 at 10 and having the flange 11 engaging over the top of the head 7. The 15 nut 9 has the spaced lugs 12 thereon to receive a suitable wrench for turning.

The transverse shaft 13 is rotatably mounted in the body 1 in the bearings 14 and 15. It has the tapered shank 16 adapted to receive a suitable gear or coupling for driving the shaft. The shaft is preferably driven at the speed of the motor crankshaft. It may, however, be driven at one-half motor speed by slightly modifying the structure to be later described as will be obvious to those skilled in the art.

The spiral pinion 17 is fixed on the shaft 13 and is enmeshed with the spiral gear 18 provided at the lower end of the cylinder 2. The angle of the spiral of the gears 17—18 is designed so 30 that the cylinder 2 is rotated at one-half the speed of the shaft 13.

The pump plunger 19 is slidable within the cylinder 2. Its lower portion is cut away to form the recess 20. The rocker arm 22 located 35 at one side of the gear 17 has the integral hub 23 fixed on the shaft 24 which is rotatably mounted in bearings such as 25. The end of the rocker arm is slightly offset and rounded off at 26 and operatively engages the recess 20 in 40 the plunger 19, see Fig. 5.

The roller 27 is provided on the opposite end of the rocker arm 22 and cooperates with the cam 28. The rises 29 displace the roller 27 to operatively raise the plunger 19 into the position 45 shown. The rises are timed to coordinate the movements of the plunger 19 with the timing of the motor as will be later described.

When the present pump is used in conjunction with a four cylinder motor, the cam 28 will be 50 provided with two rises. The spring 30 expands between the body 1 and the lug 31 on the rocker arm to urge the plunger 19 into lowered position.

The distributor head 7 has the annular feed 55

groove 32 therein, see also Figs. 2 and 3. The passage 33 leads downward from the groove 32 to the rotatable fuel supply sleeve 34. The port 35 regulates the amount of fuel supplied by the extent of its registry with the passage 33. The throttle lever 36 enables the sleeve 34 to be rotated to adjust the fuel supply as desired. The feed groove has the short radial channels 37 leading therefrom. The flange 4 has the channel 38 therein which is arranged to register successively with each of the channels 37 to supply the interior of the cylinder 2 with fuel.

The leads 39 in the head 7 are spaced a predetermined distance from the channels 37 and 15 are arranged to register with the channel 38 after it has passed from communication with the channels 37. The leads 39 are connected by means later described, to a supply of a suitable compressed gas. This gas is admitted through 20 the channel 37 into the pump cylinder 2 and mixes with the fuel previously introduced therewith. In the present instance compressed air from the motor cylinders is utilized. Obviously, however, some other gas such as pure oxygen 25 could be mixed with the fuel charge.

The outlets 40 in the head 7 register with the channel 38 on the delivery stroke of the pump plunger 19. The outlets are connected to injectors in the motor cylinders by the tubes 41. 30 The ends of the tubes 41 are welded in the unions 42 which have the lateral flanges 43. The nuts 44 threaded in the distributor head 7 engage the flanges 43 to force the unions 42 into firm engagement with the head 7. The gaskets 45 are interposed between the unions 42 and the head. The passages 46 lead from the outlets 40 through the head 7, the gaskets 45, and the unions 42 to the tubes 41.

The conduits 47 surround the tubes 41 and are 40 similarly welded to the unions 42. The annular space within the conduits is connected to the leads 39 by the passages 48, see Fig. 4, provided through the unions 42, the gaskets 45 and the head 7.

Fig. 6 shows one cylinder and the associated fuel injector of the multicylinder motor in conjunction with which the present invention is used. Since all the cylinders are alike in construction and operation, only one is illustrated and described.

The construction comprises the cylinder 50 surrounded by the usual water jacket 51. The head 52 closes the cylinder 50 and has the water jacket 53. The piston 54 operates in the cylinder 50 and 55 is operatively connected to the crank shaft of the motor in the usual manner.

The injector 55 is secured in the opening 56 in the head 52 by the clamp 57 and the bolt 58. The gasket 59 interposed between the injector and the shoulder 60 in the opening 56 prevents gas leaks past the injector. The tube 41 and its enclosing conduit 47 have their ends fixed in the union 61 which is similar in all respects to the unions 42 previously described. The coupling 62 secures 65 the union 61 to the injector 55.

The injector has the central passage 63 therein which communicates with the interior of the tube 41. The restricted orifices 64 discharge from the lower end of the passage 63 into the cylinder 50. The injector also has the passage 65 therein 70 communicating with the interior of the cylinder 50 and leading upward to the annular space within the conduit 47. This allows the egress of gases from the motor cylinder 50 to the space 75 within the conduit.

A modified form of injector is illustrated in Fig. 7. In this form, the injector 70 has the central passage 71 enlarged at 72 to receive the needle valve 73 which seats at 74 to close the passage 71. The needle valve is normally seated by the spring 75 expanding thereagainst. The setscrew 76 is adjustable to regulate the tension of this spring. The bypass 77 connects the passage 71 to the fuel tube 41.

The pressure of the fuel beneath the needle valve 73 during the injection cycle unseats the valve and permits the flow of fuel through the passage 71. When the fuel pressure diminishes at the end of this cycle, the spring 75 seats the valve 73 sharply terminating the flow of fuel 15 and preventing dripping from the injector as usual in this type of injector.

The passage 78 communicates with the motor cylinder through the bottom of the injector and discharges into the enlarged portion 72 of the 20 central passage above the needle valve 73. The short passage 79 leads from this portion 72 to the annular space within the conduit 47. Any leakage of fuel above the stem of the valve 73 is thus conveyed back to the fuel pump through the 25 passage 79 and the conduit 47.

The apparatus operates substantially as follows: When the rise 29 of the cam passes the roller 21, the spring 33 expands and lowers the pump plunger 19. The sleeve 2 is continuously rotated 30 by the driving gear 17. This rotation brings the channel 38 into registry with the fuel channel 37 during initial portion of the above described downward stroke of the plunger. Fuel then flows into the space above the descending plunger 19. 35 The amount of the fuel admitted depends upon the extent of the registry of the regulating port 35 with the intermediate fuel passage 35, see Fig. 2. The channel 38 passes from registry with channel 37 while the plunger 19 is still executing 40 its downward stroke.

The continued rotation of the cylinder 2 carries the channel 38 into registry with the lead 39. The piston 54 in the cylinder 50, see Fig. 6, into which the fuel charge is to be subsequently injected, is simultaneously executing its compression cycle. Air thus compressed in the cylinder 50 flows upward through the passage 65 into the annular space within the conduit 47. From thence, it passes through the passage 48, the lead 39, and the channel 38 into the pump cylinder 2 above the plunger 19. The continued downward movement of the plunger aids in this transfer of air from the cylinder 50 to the pump cylinder 2. The channel 38 passes from registry 55 with the lead 39 after the plunger 19 terminates its downward movement. This cuts off all communication from the pump cylinder 2.

The upward stroke of the pump plunger 19 is accomplished by the rise 29 of the cam displacing 60 the roller 21. The mixture of fuel and air above the plunger is compressed until it reaches the usual injection pressure. The internal heat of the compressed air raises the temperature of the fuel mixture to near the ignition temperature 65 at the given pressure. When the fuel mixture reaches the above pressure, the channel 38 passes into registry with the outlet 40. The fuel mixture then flows through the passage 46, the tube 41, and the injector 55 and is injected into the 70 motor cylinder through the orifices 64. The operation of the pump is coordinated with the motor so as to commence injection at the usual point in the cycle of operation of the motor cylinder.

The flow of compressed air through the conduit 47 immediately preceding the injection cycle, as hereinbefore described, preheats the tube 41 and surrounds it against loss of heat by an insulating 5 blanket of hot air. The fuel charge is thus injected into the water cylinder at nearly the temperature to which it was raised in the pump cylinder, thus promoting combustion.

At the end of the injection cycle, the plunger 10 19 begins its downward movement just before the channel 38 passes from registry with the outlet 40. This relieves the pressure in the passages leading to the injector thus sharply terminating the injection cycle and obviating any subsequent 15 slow dripping of fuel from the injector.

The channel 38 next passes into registry with the succeeding fuel supply channel 37. The cycle of operation of the pump is then repeated and fuel injected into another cylinder of the motor.

Having thus described this invention, what is claimed and desired to secure by Letters Patent is:

1. A fuel pump for internal combustion motors including a body having a pump chamber therein; a plunger slidable in said chamber; means for reciprocating said plunger; a distributor head fixed on said body and having therein a fuel supply groove, a lead communicating with a source of compressed gas, and an outlet communicating 25 with a fuel injector; a member rotatably mounted in said body in slidable engagement with said head and having a channel therein communicating with said pump chamber and adapted to register successively with said fuel supply groove, 30 said gas lead, and said injector outlet; and means for driving said rotatable member in timed relation to said reciprocating plunger so that said channel registers with said fuel supply groove and said gas lead during the intake stroke of 35 said plunger and with said injector outlet during the discharge stroke of the plunger.

2. A fuel pump for internal combustion motors including a body; a hollow cylinder rotatably mounted in said body and having a radial channel therein communicating with the interior of the cylinder; a plunger slidably mounted within said cylinder; means for reciprocating said plunger; a distributor head slidably engaging that portion of said cylinder having said channel 45 therein and having therein a fuel supply groove, a lead communicating with a source of compressed gas, and an outlet communicating with a fuel injector; and means for rotating said cylinder in timed relation to said reciprocating plunger; said channel being brought, by the rotation of said cylinder, into registry with said fuel supply groove and said gas lead successively during the intake stroke of said plunger and said injector outlet during the discharge stroke of 50 said plunger.

3. In a multi-cylinder internal combustion

motor; a fuel pump including a body; a hollow cylinder rotatably mounted in said body and having a radial channel therein communicating with the interior of the cylinder; a plunger slidably mounted within said cylinder; means for reciprocating said plunger; a distributor head slidably engaging that portion of said cylinder having said channel therein and having a plurality of equiangularly spaced outlets communicating with fuel injectors associated with the cylinders of said 5 motor, leads spaced a predetermined angular distance from each of said outlets and communicating with a source of compressed gas, and a fuel supply groove having channels spaced a predetermined distance from each of said leads; and 10 means for rotating said cylinder in timed relation to said reciprocating plunger; said radial channel being brought, by the rotation of said cylinder, into registry with one of said fuel channels, and the adjoining gas lead successively during 15 the intake stroke of said plunger and the adjacent injector outlet during the discharge stroke of said plunger.

4. In combination with a cylinder of an internal combustion motor; a fuel injector associated with said cylinder; a fuel pump having a chamber therein and an outlet, a lead, and a fuel supply means, all normally sealed from said chamber; a plunger slidably mounted in said chamber; means for reciprocating said plunger; 25 a tube connecting said outlet to said injector; a conduit enclosing said tube and providing communication between said lead and the interior of said cylinder; and means for providing communication, between said fuel supply means and 30 chamber on the initial portion of the downward stroke of said plunger, between said lead and said chamber on the latter portion of said downward stroke of the plunger, and between said outlet and said chamber on the upward stroke of the 35 plunger.

5. A fuel pump for internal combustion motors including a body; a hollow cylinder rotatably mounted in said body and having a lateral flange thereon with a radial channel therein communicating with the interior of the cylinder; means for rotating said cylinder; a distributing head fixed on said body slidably engaging said flange and having therein, a fuel supply groove, a gas supply lead, and an outlet, all arranged to register with said channel in succession as said cylinder rotates; a plunger slidably in said cylinder; a rocker arm operatively engaging the end of said plunger; and a cam arranged to oscillate said rocker arm so as to reciprocate said plunger in 55 timed relation to the rotation of said cylinder so that said channel registers with said fuel supply groove and said gas lead during the intake stroke of said plunger and with said outlet during the discharge stroke of the plunger.

WALDO G. GERNANDT.
